UNITED STATES PATENT OFFICE.

WILLIAM H. EVANS, OF BOSTON, MASSACHUSETTS.

TONGS.

SPECIFICATION forming part of Letters Patent No. 276,572, dated May 1, 1883.

Application filed September 19, 1882. (No model.)

To all whom it may concern:

Be it known that I, WILLIAM H. EVANS, of Boston, in the county of Suffolk and State of Massachusetts, have invented certain new and 5 useful Improvements in Tongs, of which the following is a full, clear, and exact description.

This invention relates to tongs more especially designed for use in removing articles 10 from show-windows of stores, and from other places inconvenient of access with the hands alone.

This improved tong is composed of two jaws, which are carried by a handle of sufficient length, one jaw being arranged to be closed upon the other against a spring by mechanism connected to it and running to a convenient part of the handle to be operated by the hand grasping the handle, and to be opened 20 by the reaction of said spring, and both jaws are hung upon the handle, and are capable of being changed and set in position, all as hereinafter fully described.

In the accompanying plate of drawings my 25 improved tongs are illustrated. Figure 1 is a side view on a reduced scale. Figs. 2 and 3 are views, respectively, of different edges of the jaws to the tongs and a portion of the handle. Fig. 4 is a side view, on an enlarged scale, 30 of the jaws to the tongs and the end of the handle to which they are attached. Fig. 5 is a central longitudinal section of Fig. 4. Fig. 6 is a transverse vertical section on an enlarged scale and on line 6 6, Fig. 1.

35 In the drawings, A is the stick or handle, made of any suitable length for the use intended. This handle at one end carries two jaws, B and C, both hung upon a center-pin, a, at one end, so as to be opened from and 40 closed upon each other, working against a spring, b, in the closing of the jaws and with the reaction of said spring in the opening of the jaws. The center-pin a is fastened to the jaw C, and it passes loosely through the 45 jaw B, and also through the end d of the handle A, and thus the two jaws can be swung

upon the handle and changed in their position as to the length of the handle—as, for instance, as shown in Fig. 4 in dotted lines. The jaw C has a series of notches, f, and the 50 handle a spring catch-wire, g, for engaging by its part h with said notches, all so that by the engagement with the catch-wire g with a notch, f, of the jaw C the adjustment of the jaws as to the length of the handle may be made 55 .

l is a string or wire fastened to the jaw C, and from thence passing through a slot, m, in the jaw B, partially around a guide-pulley, n, and thence along the length of the handle A, through 60 guide-loops r, toward the end s of the handle, which is grasped by the hand, and there it is provided with a sliding finger-piece, u, for operating the line to close the jaw C upon the article to be seized by the tongs, and thus to 65 grasp it between such jaw and the other jaw B.

These tongs enable articles to be grasped for removal from or insertion in a store-window, &c., which would be most inconvenient and impossible to do with the hands alone, and as 70 both jaws are capable of the adjustment upon the handle described they can be put into the most convenient position for operation.

Having thus described my invention, what I claim, and desire to secure by Letters Patent, 75 is—

1. Tongs composed of two jaws, B C, hinged to a handle, A, and arranged to be adjusted upon said handle, and to be closed and opened substantially as described, for the purpose 80 specified.

2. Tongs composed of two jaws, B C, hinged to a handle, A, provided with a spring-catch; g, to engage with a notch, d, of one of said jaws, substantially as and for the purpose specified. 85

In testimony whereof I have hereunto set my hand in the presence of two subscribing witnesses.

WILLIAM H. EVANS.
